UNITED STATES PATENT OFFICE.

EUGENE W. VOGEL, OF CHICAGO, ILLINOIS, ASSIGNOR TO THE RAILROAD SUPPLY COMPANY, OF CHICAGO, ILLINOIS, A CORPORATION OF ILLINOIS.

LOCKING SYSTEM FOR RAILWAY-SWITCHES.

1,171,991.

Specification of Letters Patent. Patented Feb. 15, 1916.

Application filed February 19, 1908. Serial No. 416,798.

To all whom it may concern:

Be it known that I, EUGENE W. VOGEL, a citizen of the United States, residing at Chicago, county of Cook, State of Illinois, have invented a certain new and useful Improvement in Locking Systems for Railway-Switches, and declare the following to be a full, clear, and exact description of the same, such as will enable others skilled in the art to which it pertains to make and use the same, reference being had to the accompanying drawings, which form a part of this specification.

My invention relates to railways and more particularly to means for locking switches and a control system for such means.

My invention has for one of its objects to provide a simple and compact switch lock of novel construction.

A further object of my invention is to so construct and arrange an electrically controlled switch lock so that it may also act as a circuit maker or a circuit breaker, thereby avoiding the necessity of auxiliary contact devices which are usually associated with switches in addition to the lock device itself.

A further object of my invention is to provide a switch lock which will operate to control a switch arranged on either side thereof without requiring a reversal of the lock and its supporting casing.

A further object of my invention is to provide a novel system of distant control for a switch lock together with return indicating means controlled by the lock or its actuating mechanism.

The various features of novelty whereby my invention is characterized will be hereinafter pointed out with particularity in the claims; but for a full understanding of my invention and of its various objects, some of which have just been enumerated, reference may be had to the following detailed description taken in connection with the accompanying drawings, wherein:

Figure 1 is a side elevation of a preferred form of switch lock housed within its inclosing casing; Fig. 2 is a plan view with the

cover removed; Fig. 3 is a view, partly in section and partly in side elevation, taken on line 3—3 of Fig. 2; Fig. 4 is a transverse section taken on line 4—4 of Fig. 3; Fig. 5 is a diagram showing a section of track having a switch therein together with a controlling circuit for said switch extending from a remote point; and Figs. 6, 7, and 8 are diagrams similar to Fig. 5 showing different arrangements of control circuits.

Referring to the drawings, A is a casing open at the top and preferably made in the form of a single casting.

a, a are feet whereby the casing may be secured to the ties or other supporting structure at a point adjacent a switch. Within the casing and preferably integral therewith are a pair of aligned hubs or bosses A' and A². These hubs or bosses do not meet at the center of the casing. Journalled within these bosses is a stub shaft B, this shaft extending entirely through the hub A' and the corresponding side wall of the casing and being seated in a closed bearing a² in the companion hub. The shaft may be held in position by means of a pin C which is carried by the hub A² and extends into a groove b in the inner end of the shaft. This pin permits the shaft to rotate within its bearing but prevents axial displacement.

On the outer end of the shaft is a crank-arm B' to which is pivotally secured one end of a rod B². The other end of this rod is adapted to be secured to the switch points so that when the switch points are moved the crank-arm and its connected shaft are oscillated. In the drawings the parts are shown in the positions which they occupy when the switch is locked, a longitudinal slot b' in the shaft being now on the upper side. The slot b' is adapted to receive the lower end of a key D which is slidably mounted within bearings a⁵ and a⁶ in the ends of the hubs A' and A², respectively. When free to do so the key drops into the groove or slot and holds the shaft securely against rotation. It will be seen that the key is securely supported at its ends in the rigid structure of the casing and that any tend-

ency on the part of the shaft to rotate is resisted entirely by the key and the casing, so that no strain comes upon the operating mechanism for the key. This mechanism 5 may therefore be made light and sensitive.

E is a magnet of any suitable type suitably mounted within the casing at one side of the shaft. The armature e of this magnet is carried upon an arm f projecting downward from one end of an elongated arm F which is pivotally supported intermediate its ends as at f'. The opposite end of the arm F is connected to the key in any suitable manner, as for example, by means of links f¹, f² which are pivotally connected at their 10 opposite ends to the arm and to the key, respectively. The parts are so proportioned that, when the magnet is energized, the armature is attracted and causes an oscillation 15 of the arm F in such a direction that the front end to which the key is attached rises, thereby lifting the key out of engagement with the shaft. A convenient method of supporting the arm F is to extend the 20 bracket E' which passes across one end of the magnet, and to provide a fork e' in the upper end of this bracket; the lever-arm lying within this fork and being supported upon adjustable bearing screws or the like e². 25

The end of the lever arm is preferably 30 extended somewhat beyond the point of connection with the key, as at F', so as to provide a support for switch contacts. The portion E' may conveniently be made T-shaped, each arm of the T carrying one of 35 the contact members G and G'. Each of the contact members may conveniently be provided with a pair of spring fingers g and g' respectively, one of the fingers being adapted 40 to engage with a fixed contact when the parts are in locking position and the other finger being adapted to engage with a second fixed contact when the parts are in the unlocking position. The contact members 45 G and G' are insulated from each other and from the lever by means of posts of insulating material H. The members G and G' are connected to binding posts or other terminals I and I' respectively. The fixed contacts with which the fingers g and g' are 50 adapted to coöperate are indicated at K and K' respectively, each of these fixed contacts comprising an upper member k adapted to coöperate with one of the fingers g, and a lower member k' for coöperation with one 55 of the fingers g'. The members k and k' are of course insulated from each other so that the terminals I and I' are connected in different circuits in the locking and 60 unlocking positions of the parts.

It is often desirable to have a circuit breaker or a circuit closer, or both, which 65 will come into play when a switch has actually been thrown into one position or the other. It has heretofore been customary,

where such a circuit controlling device has been required, to have an auxiliary switch mechanism arranged adjacent to and connected to the switch points for operation thereby. In accordance with my invention 70 I associate with the switch lock all of the circuit controlling devices which may be desired, inclosing all of such devices within the same casing as the lock itself. The cost of installation is thereby reduced, less difficulty is experienced in making the installation, since it is necessary to find room for only a single casing; and the efficiency of a system is increased because there is less liability of disarrangement of or injury to 75 the various mechanisms where they are all assembled together in a single strongly built casing. The switch device G, G' and K, K', being controlled directly by the lifting mechanism for the locking key, may be utilized to control any circuits which may be desired for giving an indication or controlling a signal or the like when the locking magnet has been fully energized and has caused the locking key to be lifted. In order to control circuits which are to become operative or inoperative as the case may be, when the switch is in one position or the other, I provide a further switch mechanism 80 which is not operated simply by the actuating mechanism for the locking key, but which requires the switch points to be thrown into one position or the other in order to effect a change in the circuit conditions. Since the shaft B moves in synchronism with the switch points, such auxiliary contact devices may conveniently be actuated directly by this shaft, thereby making it possible to place them wholly within the casing. In the drawings I have shown a 100 lever or arm L pivotally mounted upon a bracket l so as to bring one end into proximity to the shaft. A shoulder b² is formed upon the shaft, either by cutting away part 105 of the shaft or otherwise, at such a point that, upon oscillation of the shaft from the position shown, the shoulder engages with the adjacent end of the member L or a roller L' carried thereby, and oscillates the arm about its pivot. The arm may conveniently be provided with an elongated section of insulation L² carrying separate contact pieces l² and l³. Normally the contact piece l² 110 bridges a pair of stationary contact fingers m, m. Upon rotation of the shaft and oscillation of the member L the connection between the contact pieces m, m is interrupted and the contact piece l³ is brought into engagement with and bridges a second set of 115 fixed contacts m', m'. Consequently the member L may be employed to control two different circuits, one of which is closed when the switch points are in one position and the other of which is closed when the switch points are thrown into the other position. 120

sition. It will be seen that the member L will be oscillated in the same manner irrespective of the direction of rotation of the shaft from the position indicated, and therefore the lock may be connected to a pair of switch points lying either to the right or to the left of the casing as viewed in Figs. 1 and 3.

L³ is a spring which bears against the member L so as to retain it in the position indicated in the drawings when free to do so. This switch member is therefore positively moved in one direction whenever the switch points are thrown and is returned to its normal position through spring pressure. It will be of course understood that the number and arrangement of the contacts may be varied to suit any desired conditions, since those which I have illustrated are simply examples of satisfactory forms of circuit closing devices which depend for their operation either upon an unlocking of the track switch or upon actual movement of such switch from one position to another.

On account of the nature of the mechanism contained within the casing it is desirable to have a cover of some sort which will effectually prevent tampering with the contents of the casing and also prevent the entrance of moisture or dirt into the casing. At the same time the closing device should be such that access may readily be had to the interior of the casing without making it necessary for the operator to unscrew a number of nuts or bolts or other similar fastening devices: for screw-threaded devices are not only expensive and unsatisfactory in other ways, but they are apt to rust or corrode so that it might be impossible to open the casing without considerable difficulty and without, perhaps, breaking some of the parts. I have illustrated a very simple and effective closure which may readily be removed and replaced without the use of special tools and which, when in place, securely seals the casing.

A³ indicates a cover which may take any desired form, the only essential requirement being that the cover shall completely close the top of the casing. A groove a⁷ is formed in the under side of the cover, this groove being somewhat wider than the thickness of the side walls of the casing and being of such a shape that when the cover is properly superposed upon the casing, the top edges of the side walls of the casing will enter into the groove. A gasket a⁸ of felt or other suitable material rests directly upon the upper edge of the casing and forms a complete seal between the casing and the cover.

A⁴ is a hasp secured to one end of the casing by means of a staple A⁶ which is riveted or otherwise fastened in place, one leg of the staple passing through a perforation in the hasp. At the free end of the hasp is a

pivoted tongue A⁶ which is adapted to be swung over a second staple A⁷ at the opposite end of the casing.

In Figs. 1 and 3 the cover is shown upon the casing and the hasp in the secured position. By placing a lock through the staple A⁷, as indicated at N in Fig. 1, the cover is securely held in place and cannot be removed without first removing the lock. The hasp is preferably made of spring metal which is bent so that when the tongue A⁶ is removed from the staple the hasp assumes the position shown in dotted lines in Fig. 1. In order to engage the tongue with its staple it is necessary to press down upon the end of the hasp and therefore, after such engagement has been effected, the hasp will be exerting a downward pressure upon the top of the cover throughout the entire length thereof and the joint between the cover and the casing will be maintained tight under all conditions on account of this pressure.

In Fig. 5 there is illustrated a system in which a portion of the contact devices of my improved locking apparatus are utilized. Thus O is a switch with which the lock is associated and P is a push button located at a remote station from which the lock may be controlled. When the operator at the station presses the button a circuit is established from the right hand side of battery P', through the lock magnet E, through the contacts m, l², and m, through a circuit breaker or the like associated with a signal P², through the push button; through magnet P³ controlling an indicator, and thence to the left hand terminal of the battery. By pressing the button the locking magnet is energized and the switch unlocked; simultaneously the indicator at the station is set; as soon as the switch is actually thrown the circuit of the locking magnet is interrupted at the contact m, m and the indicator drops to its normal position.

In Fig. 6 I have shown a slightly modified arrangement. Upon throwing the switch Q to the left a circuit is completed from battery Q' through a dwarf signal Q², the contacts m, m, and l² being included in this circuit. The switch must therefore be occupying a predetermined position before the signal can be operated. By throwing the double-throw switch to the right a circuit is completed through battery Q³, through the locking magnet E, and through a bell Q⁴ located adjacent the outlying switch. By this arrangement the switch is unlocked and the trainman is notified through the ringing of the bell that this is so.

In Fig. 7 there is shown an arrangement wherein still more of the auxiliary contact devices are brought into play. Assuming that there is a trainman at the outlying switch: he can call the attention of the op-

erator at the station by pressing the push button B. A circuit is thereby completed through a bell R' at the station and the lower half of a battery R². If the track is 5 clear, the operator may, by closing contact maker R³, unlock the switch, the closing of this contact maker completing a circuit from the battery R² through the locking magnet. As soon as the locking magnet is energized 10 in the manner described, the locking key is lifted so that the switch may be thrown. Upon the lifting of the locking key one of the contacts g engages with its coöperating contact k and a circuit is completed as follows: from the lower end of the battery R² through wire r, through contacts g and k, through contacts m, l², m, through bell R⁴, through wire r', through bell R' back to the top of the lower half of the battery. There- 15 fore as soon as the locking key is lifted the bells at the station and at the outlying switch begin to ring and continue to ring until the switch is actually thrown, the throwing of the switch of course interrupting the bell circuits at contacts m, m. As 20 soon as the switch is thrown a circuit may be traced from the lower half of the battery through wire r², through an indicator R⁵, at the station, through wire r³, through contacts m', l³, m' thence by way of wire r back to the battery. Consequently the indicator at the station is actuated so as to show 25 that the switch has been thrown.

Fig. 8 illustrates a still different arrangement. If a trainman at the outlying switch desires to attract the attention of the operator at the station he presses the push button S and thereupon a circuit is established from the lower end of the battery S' 30 through wire s', through the push button S, through wire s², through the bell S² back to the battery. The bell S² is therefore caused to ring. In the same way the operator can 35 attract the attention of the trainman by pressing the button S³ at the station. There- 40 upon a circuit is established from the intermediate terminal of the battery through the push button S³, through wire s³, through the bell S⁴ adjacent the switch, through wire s' back to the battery. When the operator 45 desires to unlock the switch he closes the contact maker s⁶ and thereupon a circuit is 50 established from the upper terminal of the battery through the contact maker, through wire s⁴, through the locking magnet and thence by way of wire s' back to the battery.

S⁷ is an indicator at the switch and by 55 tracing the circuits passing through this 60 indicator it will be seen that the indicator is connected to wires s' and s⁴ in parallel with the locking magnet; it being necessary, however, for the completion of this indicator circuit that one of the contacts g be in 65 engagement with its coöperating contact k.

Therefore the indicator will not be actuated, even when the locking magnet is energized, until after the unlocking has been completed: then the indicator will be set and the trainman will be apprised of the fact 70 that the switch is in condition to be thrown. In this arrangement, also, both of the bells will begin to ring when the lock is fully released and will continue to ring until the switch is thrown and the bell circuit interrupted. This particular bell circuit is as follows: from the lower terminal of the battery through wire s', through wire s⁵ through the bell S⁴, through wire s⁶ through the right hand contact g and k, through wire s⁷ through contact m, l², m, through wire s², through the bell S² to the intermediate terminal of the battery. After the switch has been thrown the indicator S⁸ 75 at the station will be actuated so as to acquaint the operator with this fact. The indicator circuit may be traced as follows: from the intermediate terminal of the battery, through the indicator, through wire s⁸, through contacts m', l³, m', through wire s⁹, through wire s¹⁰, and wire s' back to the lower terminal of the battery.

While I have illustrated and described only a few simple circuit arrangements in order to make it clear in what manner the contact devices may be utilized, I do not desire to be limited to the particular circuit arrangements disclosed, for in its broader aspects my invention is applicable to various other circuit schemes or systems. Furthermore, the various mechanical details illustrated do not define the bounds of my invention, considered as locking and circuit closing mechanism, but are only intended to illustrate my invention by means of particular embodiments which have been found by actual practice to be satisfactory.

Having now fully described my invention, what I claim as new and desire to secure by Letters Patent is:

1. In a switch lock, a casing having alined inwardly projecting hubs, a revoluble shaft journaled in said hubs but prevented from moving axially therein, shoulders on the adjacent ends of said hubs arranged transversely of said shaft, shoulders on said shaft in position to aline with the shoulders on the hubs when the shaft occupies a predetermined position, a key interlocked with the shoulders on the hubs so as to be free to move into and out of engagement with the shoulders on the shaft and at the same time be held against a movement in the transverse direction, and means for actuating said key.

2. In a switch lock, a casing having alined inwardly projecting hubs, a revoluble shaft journaled in said hubs but prevented from moving axially therein, shoulders on the adjacent ends of said hubs arranged trans-

versely of said shaft, shoulders on said shaft in position to align with the shoulders on the hubs when the shaft occupies a predetermined position, a key in engagement with the shoulders on the hubs so as to be free to move into and out of engagement with the shoulders on the shaft and at the same time to be held against a movement in the transverse direction, and a lever pivotally

connected to the outer end of the key for 10 moving the same from and toward the shaft.

In testimony whereof, I sign this specification in the presence of two witnesses.

EUGENE W. VOGEL.
